DESIGN FOR AN ELECTRICAL CONTACT ELEMENT

Guy H. Burt, Providence, R. I.

Application October 31, 1941, Serial No. 103,967

Term of patent 14 years

To all whom it may concern:

Be it known that I, Guy H. Burt, a citizen of the United States of America, residing in Providence, county of Providence, State of Rhode Island, have invented a new, original, and ornamental Design for an Electrical Contact Element, of which the following is a specification, reference being had to the accompanying drawing, forming a part thereof.

The figure in the drawing is a perspective view

of an electrical contact element showing my new design.

The dominant feature of the design resides in the portion of the electrical contact element shown in full lines.

I claim:

The ornamental design for an electrical contact element, substantially as shown and described.

GUY H. BURT.
